UNITED STATES PATENT OFFICE.

CLAUDIOUS M. CROCKER, OF SPOKANE, WASHINGTON, ASSIGNOR OF ONE-FOURTH TO JOHN F. POMEROY AND ONE-FOURTH TO GRANVILLE O. DAVIS, BOTH OF KAMIAH, IDAHO.

RAIL-JOINT BRACE.

1,262,754.

Specification of Letters Patent. Patented Apr. 16, 1918.

Application filed August 25, 1917. Serial No. 188,184.

To all whom it may concern:

Be it known that I, CLAUDIOUS M. CROCKER, a citizen of the United States, residing at Spokane, in the county of Spokane 5 and State of Washington, have invented new and useful Improvements in Rail-Joint Braces, of which the following is a specification.

The present invention relates to improvements in rail joints and is particularly directed to truss braces employed for strengthening the joints.

In carrying out my invention it is my purpose to provide a truss brace for rail joints which will effectively prevent the sinking of the rails at the joints thereof.

It is also an object of the invention to provide novel means for holding the truss in positive engagement with the rails.

Other objects and advantages will appear as the nature of the invention is more fully understood, reference being had to the accompanying drawings, in which,

Figure 1 is a side elevation of two connected rails, illustrating the application of my improvement.

Fig. 2 is a top plan view of the same.

Fig. 3 is an enlarged sectional view approximately on the line 3—3 of Fig. 2.

Fig. 4 is an inverted plan view of the device.

Fig. 5 is a perspective view of the plate designed to underlie one of the ties.

Fig. 6 is a perspective view of one of the rail reinforcing plates.

Fig. 7 is a perspective view of one of the truss rods.

Fig. 8 is a side elevation illustrating a modified form of construction.

Fig. 9 is a top plan view of the same.

Fig. 10 is a perspective view of one of the rail engaging members or plates.

Referring now to the drawings in detail, the rails are indicated by the numerals 1—1,

the same being alined and having abutting ends which are connected, by the usual nuts and bolts, with angle plates 2—2. The rails are supported upon the usual ties 3, and one of these ties is disposed directly beneath the joint of the rails.

Arranged upon the bottom face of the last referred to tie 3 is a flat metallic plate 4, the same having its edges ribbed as at 5, the said ribs being disposed at the opposite

sides of the tie, and if desired, may engage 55 with the sides of the tie. The plate 4 inward of its rib 5 adjacent its ends is formed with openings 6—6, each of said openings being disposed a suitable distance from one of the corners of the tie, and these openings 60 are designed to receive the hook ends 7 of truss rods 8. The rods 8 are of a length to pass through angularly disposed openings 9 in the base flanges of the respective rails 1, the said openings being of a greater diameter 65 than the diameter of the truss rods 8.

To reinforce the rails at the portions thereof, provided with the openings 9, I provide rail plates 10, each of the said plates having its opposite faces provided 70 with angularly disposed alining bosses 11 and 12 respectively, the periphery of the boss 11 being preferably elliptical to correspond with the shape of the openings 9 in the base flanges of the rails, and also 75 whereby the said plates 10 will be held against lateral or turning movement. The bosses 11 and 12, as well as the plates 10 are provided with alining openings 13, and it is through these openings that the threaded 80 ends of the rods 8 pass. The boss 12, upon the outer end thereof, is formed with a socket 14, designed to provide a rest or pocket for one end of convolute springs 15, one of said springs being arranged upon 85 each of the rods 8. Upon the outer ends of the rods 8 are threaded nuts 16, and also arranged upon the said rods, contacted by the said nuts 16 are washer members 17, the said washers contacting with the outer ends 90 of the springs 15. The springs exerting a tension between the washer member 17 and the bosses 12 have a tendency to draw the rods 8 outwardly through the said bosses and cause the hooked ends 7 thereof to 95 tightly engage with the ribs 5 of the plate 4, and consequently, force the said plate 4 in frictional contact with the under face of the tie 3.

From the arrangement as above described, 100 it will be noted that the tension of the springs may be regulated by adjusting the nuts 16 and also that the openings provided in the base of the rails are reinforced by the bosses 11 of the plates 10. It will be further 105 noted that, by adjusting the nuts 16, the proper tension between the rods 8 and the plates 4 may be readily obtained so that the

tie 3, directly below the joint of the rails may be brought into proper contact with the under face or base of the said rails. In some instances, it may be found desirable 5 not to form openings in the base of the rails, as in spite of the manner in which the plates 10 and their bosses 11 reinforce the rails, it may be held that by providing the said rails with the openings 9, the same may attempt 10 to weaken the rails. Therefore, in Figs. 8 to 10, I have illustrated a construction wherein the truss rods will amply support the rails at the joint without providing the said rails with openings, or in otherwise interfering with the construction thereof. In 15 the said figures, and at any desired distance from the abutting ends of the rails 20—20, I arrange upon the base or foot of the said rails, plate or block members 21. The members 20 are preferably constructed of metal and are centrally channeled in a transverse direction upon their upper faces providing a flat surface 22 upon which the bases of the rails rest, and angular portions 23 extending 25 in opposite directions over the said flat surface 22 and shaped to engage with the outer surface of the base or foot of the rails. The members 23 are in the nature of lips and are provided with suitable threaded openings 30 through which are passed headed threaded elements 24, any suitable means being provided for holding the said elements 24 when the same are brought to frictional contact with the rails, and whereby the members 21 35 are effectively retained upon the said rails. The members 21 are, of course, of a length considerably greater than the width of the rails at the base thereof, and the portions thereof, at the opposite sides of the rail seat, 40 are provided with angular openings through which pass the truss rods 25, the said truss rods having their inner ends hooked to pass through the openings in the plate 26 which underlies the central tie 27, the latter being 45 disposed directly under the rails at the meeting ends thereof. The opposite ends of the truss rods are threaded and have screwed thereon nuts 28, springs 29 being arranged upon the said rods between the said nuts and 50 the plate or block members 21. The rods, it will be noted, are of a construction similar to that previously described, as is also the tie plate, and from the foregoing description, when taken in connection with the 55 drawings, the advantages of construction will, it is thought, be apparent without further detailed description, it being understood that the members 21 are slipped over

the base of the rails before the said rails are brought into contacting relation. 60

Having thus described the invention, what I claim is:

1. The combination with the meeting ends of rails, angle bars connecting the rails and a tie arranged directly beneath the meeting ends of the rails, of a ribbed plate upon the under face of the said tie, truss rods 65 removably connected to the plate and having threaded ends which pass through openings in the base flanges of the rails, rail plates 70 provided upon their opposite faces with bosses, one of which being received in the respective openings in the rails, the plates and bosses having alining openings through which the truss rods pass, an adjustable element 75 upon the outer end of each of the truss rods, and a spring between the said element and the outer boss of the respective plates.

2. In combination with rails, connecting means for the rails, a tie disposed below the meeting ends of the rails, of a plate arranged beneath the tie and having ribbed edges which contact with the tie, said plate having an opening adjacent each of the corners thereof, the base flanges of the rails 80 having angularly disposed openings which are of an elliptical formation, truss rods having hook ends engaged in the respective openings of the tie plate, rail plates having their opposite faces provided with angularly 85 disposed alining bosses registering with the openings in their respective plates and through which the ends of the truss rods are adapted to pass, the inner boss being elliptical and being received in the elliptical 90 openings in the rails, the upper bosses being recessed to provide pockets, an adjustable element upon the outer end of each of the truss rods, washers upon said truss rods, a spring upon each of the truss rods engaging 100 the respective washers, and each of said springs being received in the referred to pocket in the outer boss of each of the rail plates.

3. The combination with the meeting ends 105 of two rails, angle bars connecting the rails and a tie arranged directly beneath the meeting ends of the rails, of a ribbed plate upon the under face of the said tie, truss rods 110 removably connected to the plate, plates upon the rails, means for securing the said plates to the base of the rails, and means for adjustably connecting the truss rods to the said plates.

In testimony whereof I affix my signature. 115
CLAUDIOUS M. CROCKER.
